UNITED STATES PATENT OFFICE.

LOUIS N. D. WILLIAMS, OF OGONTZ, PENNSYLVANIA.

MECHANISM FOR LOCKING TOGETHER THE NEEDLE-CARRIERS OF RIB-KNITTING MACHINES.

1,168,041.

Specification of Letters Patent. Patented Jan. 11, 1916.

Application filed June 24, 1914. Serial No. 846,946.

To all whom it may concern:

Be it known that I, LOUIS N. D. WILLIAMS, a citizen of the United States, residing in Ogontz, Pennsylvania, have invented 5 certain Improvements in Mechanism for Locking Together the Needle-Carriers of Rib-Knitting Machines, of which the following is a specification.

My invention relates to a novel construction of the dogs whereby the cylinder and dial of a rib knitting machine are retained 10 in proper relation to one another. These dogs are disposed one on the inside and one on the outside of the tubular web of fabric 15 passing down through the machine, and usually one dog acts upon the other through the medium of the interposed web of fabric, with the result that the web is compressed 20 between the dogs wherever they occur. One result of this is to interfere with the free 25 passage of the web from the needles to the take-up mechanism and consequently with the proper tension upon the web, and another result is to form lines of compression upon the finished fabric wherever the dogs occur, which materially mar the appearance 30 of the fabric.

The object of my invention is to overcome 35 these objections, and this object I attain by 40 providing one of the dogs with teeth which project through the web so that the contact points of the dogs are upon one and the same side of said web and do not compress 45 the same.

In the accompanying drawings—Figure 1 is a view, partly in transverse section and partly in elevation, of sufficient of a rib knitting machine to illustrate one construction and arrangement of dogs in accordance 50 with my invention; Fig. 2 is a view, partly in plan and partly in horizontal section, on the line *a—a*, Fig. 1; Fig. 3 is a view, partly in elevation and partly in vertical section, on the line *b—b*, Fig. 2; Fig. 4 is a view similar to Fig. 1 but illustrating a modified construction and arrangement of dogs in accordance with my invention; Fig. 5 is a view, partly in plan and partly in horizontal section, on the line *c—c*, Fig. 4; Figs. 55 6 and 7 are views similar to Fig. 1, but illustrating still other modifications in the construction and arrangement of the dogs; Fig. 8 is a horizontal section on the line *d—d*, Fig. 6, and Fig. 9 is a horizontal section on the line *e—e*, Fig. 7.

In the drawings, 1 represents part of the

needle cylinder of the machine and 2 part of the dial, these parts being either stationary or rotating, depending upon the type of machine to which the invention is applied. 60 The dogs, however, are the same in either case, being intended to prevent circumferential movement of the dial in respect to the cylinder. The dog which is carried by the cylinder consists, as shown in Fig. 3, of a 65 toothed disk 3 mounted by means of a ball bearing upon a stud 4 which is screwed into a bracket 5 bolted to the inner side of the cylinder 1, as shown in Figs. 1 and 3.

The dog which is carried by the dial 70 consists of a disk 6 rotatably mounted upon a stud 7 carried by one arm of a lever 8 pivotally mounted on the underside of the dial, as shown in Fig. 1, and having in connection with its other arm adjusting means 75 whereby the disk 6 may be moved laterally in respect to the disk 3 to facilitate the passage of the knitted web between them prior to the adjustment of the dogs in bearing relation to one another. Any desired means 80 for mounting the dog upon the dial may, however, be adopted without departing from the essential feature of my invention.

The inner face of the disk 6 bears against 85 the sides of the projecting teeth of the disk 3 and the web passes down between the peripheral faces of the disks 3 and 6 which are far enough apart to permit the free passage 90 of the web between them without any pressure thereupon, the contact surfaces of the disk 6 and the teeth of the disk 3 being wholly upon the inside of the web.

In the construction shown in Figs. 4 and 5 the disk 6^a constitutes the toothed disk and has separated rows of teeth, as shown in 95 Fig. 5, the disk 3^a being grooved, as there shown, so as to provide two flanges one for bearing against the teeth of one row and the other for bearing against the teeth of the other row, thus providing double engagement and thereby lessening the strain upon the individual teeth, the teeth of one row being preferably staggered in respect to those of the other row as shown in Fig. 5, so as to shift the engagement of the teeth 100 with the web from one row to the other at frequent intervals.

While I prefer to employ dogs in the form of rotating disks so as to facilitate the passage of the web between the dogs, this construction is not essential to the proper embodiment of my invention. For instance,

in Figs. 6 and 8 I have shown a construction in which brackets 9 fixedly mounted on the dial are combined with jacks 10 mounted so as to reciprocate in a jack holder or holders 11 fixedly mounted on the cylinder, the inner ends of the jacks being toothed and these toothed portions, when the jack is projected, passing through the web and entering a groove in the dial bracket so as to 10 contact with one or other of the side faces of said groove, as shown in Fig. 8.

The brackets 9 and jacks 10 are distributed around the machine so as to provide a plurality of points of bearing between them and the jacks 10 have butts 12 which are engaged by a rotating cam ring 13, whereby the toothed portions of the jacks will be withdrawn in succession from the web so as to permit of the downward passage of the same, the cam ring being so formed, however, that at all times one or more of the jacks will be in the projected position so as to provide the proper locking engagement between the cylinder and dial. 25 In Figs. 7. and 9 a substantially similar arrangement is shown with the exception that the parts are reversed, the brackets 9^a being mounted upon the cylinder and the jack holder 11^a on the underside of the dial, 30 the jack operating cam ring 12^a in this case being connected by suitable arms to a ring 13^a secured to the lower end of the rotating spindle 14 of the machine. In any case the driving or locking engagement between the 35 dogs is always upon one and the same side of the fabric, on the inside in the structure shown in Figs. 1, 2, 3, 6, and 8, and on the outside in the structure shown in Figs. 4, 5, 7 and 9, so that in neither case is there 40 any clamping of the webs between the dogs or any pressure upon the web which would serve to mark the same.

Although I have shown the dogs as disposed in horizontal arrangement or circumferentially around the machine it is evident that the pairs of dogs may be disposed vertically one above another without departing from the essential feature of my invention, and although I have described the invention as applied to a rib knitting machine it is applicable to any knitting machine having two needle carrying members which at any time during the knitting operation have to be maintained in definite relation one to 55 the other.

I claim:

1. The combination of the two needle carrying members of a knitting machine with locking dogs one mounted upon one and the 60 other upon the other of said needle carrying members and engaging one another upon one and the same side of the knitted web.

2. The combination of the two needle carrying members of a knitting machine with locking dogs one on one side of the web and one on the other side of the same, one of said dogs having projecting teeth which can pass through the web and engage the other dog. 70

3. The combination of the two needle carrying members of a knitting machine, with rotating dogs carried thereby, one of said dogs having teeth which can project through the web of fabric for engagement with the 75 other dog.

4. The combination of the two needle carrying members of a knitting machine with locking dogs carried thereby and so disposed that while the knitted web passes between them they engage with one another on one and the same side of said web, and means for separating said dogs from one another so as to permit free passage of the 80 web between them. 85

5. The combination of the two needle carrying members of a knitting machine with locking dogs carried thereby, one of said dogs having teeth which can project through the web of fabric for engagement with the 90 other dog and one of said dogs being separable from the other so as to permit free passage of the web between them.

6. The combination of the two needle carrying members of a knitting machine with locking dogs carried thereby, one of said dogs having a plurality of sets of teeth which can pass through the web and the other dog having a corresponding plurality of projecting flanges for engaging with said 100 teeth. 95

7. The combination of the two needle carrying members of a knitting machine with locking dogs carried thereby, one of said dogs being mounted so as to rotate around 105 its axis and having a plurality of sets of projecting teeth for passing through the web and engaging the other dog.

8. The combination of the two needle carrying members of a knitting machine with locking dogs carried thereby, one of said dogs being mounted so as to rotate around 110 its axis and having a plurality of sets of projecting teeth for passing through the web and engaging the other dog, the teeth 115 of one set being disposed in line with the spaces between the teeth of the adjoining set or sets.

In testimony whereof, I have signed my name to this specification, in the presence of 120 two subscribing witnesses.

LOUIS N. D. WILLIAMS.
